ALBERT B. MOULTON, OF RIVERHEAD, NEW YORK, ASSIGNOR TO RADIO CORPORATION OF AMERICA, A CORPORATION OF DELAWARE

CAPACITY NEUTRALIZED SWITCH

Application filed January 27, 1927. Serial No. 163,887.

This invention relates to capacity neutralization of switching devices, and more particularly to a method and means for providing a capacity neutralized switch for the control of very high frequency energy.

It is found that an appreciable amount of high frequency energy will traverse an open switch, because of the natural capacity which exists between the contactors or poles of the switch, and its contacts. In the case of transmission energy there may be considerable radiation when even an ordinary type of knife-switch has been opened. In connection with high frequency receivers switching is often imperfect because one very convenient type of switch frequently used for this purpose possesses a rather high inherent capacity, and consequently a disconnected antenna or wire line may effect appreciable response in its receiver.

It is an object of my invention to prevent the transfer of high frequency energy over an open switch. This I propose to do by applying oppositely phased neutralizing energy to the dead side of the switch. Structurally, this is most easily accomplished by connecting the opposite side of the line to the dead side of the switch through a neutralizing capacity which is equal in magnitude to the natural capacitance of the open switch.

It is a further object of my invention to provide the necessary neutralizing capacitances in a simple and convenient manner, and to do this I employ a double throw switch instead of a single throw switch, and use the extra contacts of the double throw switch to form the desired neutralizing capacitance with respect to the contactor or pole of the switch.

In the drawing accompanying the specification,

Fig. 1 is a wiring diagram showing one method of neutralizing the capacity of a double pole single throw switch;

Fig. 2 illustrates how a double pole double throw switch may be employed to provide a capacity neutralized switch; and

Fig. 3 is a modification.

Referring to Fig. 1, the conductors 2 and

4 are connected to a source of high frequency energy, while the conductors 6 and 8 are connected to means to utilize such energy. The switch comprises poles 9 and 10, and the contacts 12 and 14. When the switch is open there is a natural capacitance c_1 between the pole 9 and the contact 12, and a capacitance c_2 between the pole 10 and the contact 14, through which high frequency energy may pass from the source to the line 6, 8, and to prevent this the neutralizing capacitance n_1 , equal to c_1 , is connected as shown, between the contact 14 and the pole 9, and the neutralizing capacitance n_2 , equal to the natural capacitance c_2 , is connected from the contact 12 to the pole 10. Since the polarity of the conductors 2 and 4 is opposite, it is clear that potentials will be applied to the dead side of the switch through the neutralizing condensers which are of opposite sign to those applied through the natural capacitances, and therefore the switch when opened will prevent the flow of high frequency energy to the line 6, 8.

The preceding description is of the more general case in which c_1 need not necessarily equal c_2 . Of course, in practice, these usually will be equal in value, and therefore the neutralizing condensers n_1 and n_2 will also be equal in value, in which case the conductors 6, 8 may be made the live side of the switch and conductors 2, 4, the dead side of the switch, as well as vice versa.

I find that a very simple way of providing the proper neutralizing condensers is to use in place of a double pole single throw switch such as was shown in Figure 1, a double pole double throw switch as shown in Figure 2. In this modification, as in the preceding, the conductors 2, 4 are one line, while the conductors 6, 8 are the other line. If the contacts 12, 19 are considered equivalent to the contacts 12, 14 in Figure 1, then the contacts 16 and 18 may be considered as neutralizing contacts, for they form, together with the poles or contactors 9, 10, capacitances n_1 and n_2 which are equal to the capacitances c_1 and c_2 , for structural reasons. The contacts 12, 19 are cross connected with the contacts 16, 18 by means of the conductors

20 and 22. The line conductor 2 has been shown connected to the contact 16 instead of the contact 19 for the reason that it is preferable to have the connections symmetrical with respect to the poles. It would, of course, be possible to connect the line 2, 4 to the contact 16, 18, or 12, 19, or 18, 19, as well as to 12, 16 as shown. Either line may be the supply or utilization line.

5 10 In the case of telephony by means of a high frequency carrier wave, difficulty is experienced in using the usual type of operating switch. The same type of switch is frequently used for the switching of radio receivers with respect to receiving antennae, and there, too, the problem of neutralization must be contended with, for the parallel contactor and contact plates of these switches possess considerable inherent capacitance.

15 20 Such a switch has been schematically represented in Figure 3. The line 2, 4 is connected to either an antenna or an incoming wire line, while the line 6, 8 is connected as shown, to the input side of any suitable receiver or amplifier, typified in this instance by a stage of push-pull amplification. The natural capacitances c_1 and c_2 are counteracted by the capacitances n_1 and n_2 , as clearly shown in the diagram. The contactors 9 and 30 10 are actuated by any suitable operating toggle 30, pivoted at 32, through the insulating rollers 34.

The foregoing is disclosed by way of illustration, and not limitation, of my invention, 35 which I claim is:

1. The method of preventing a transfer of high frequency energy thru an open mechanical switch because of its natural capacitance which consists in applying oppositely phased 40 neutralizing energy to the dead side of the switch.

2. The combination with a high frequency circuit and a mechanical switch having natural capacitance of a neutralizing condenser 45 for neutralizing the natural capacitance of the switch.

3. The combination with a high frequency circuit and a mechanical switch for its control of a neutralizing condenser arranged to 50 counteract the natural capacitance of the switch when the switch is opened.

4. A capacity neutralized switch for controlling very high frequency currents comprising a plurality of contactors, a plurality 55 of contacts for cooperation therewith to control the current, and a plurality of neutralizing elements which form with the contactors neutralizing condensers equivalent to the natural capacitances between the contactors 60 and contacts, and means to impress upon the neutralizing condensers potentials opposite in phase to those impressed upon the natural capacitances.

5. The combination with a two pole mechanical switch of a condenser substantially

equal in magnitude to the natural capacitance between a pole and its contact, connected between the pole and the contact of the other pole.

6. The combination with a two pole mechanical switch of a pair of condensers substantially equal in magnitude to the natural capacitance between each pole and its contact, connected between each pole and the contact of the other pole.

7. The combination with a high frequency circuit of a mechanical switch comprising structurally a double throw switch each having two of its contacts form with their respective contactors a neutralizing condenser for counteracting the effect of the inherent capacitance between the other respective contactors and their contacts.

8. A capacity neutralized switch for controlling very high frequency currents comprising structurally a double pole double throw switch and conductors for cross connecting its contacts, whereby the contacts form opposed capacitances with reference to the poles.

9. In combination, a supply circuit for high frequency energy, a utilization circuit for the high frequency energy, and means to connect or disconnect the supply circuit to the utilization circuit comprising a double pole double throw switch, means connecting one of said circuits to two of the switch contacts, means connecting the other of said circuits to the switch poles, and means cross connecting the contacts, whereby the contacts form opposed capacitances with reference to the poles in order to prevent energy transfer through the switch when open.
